UNITED STATES PATENT OFFICE.

JOHN M. RILEY, OF KEARNEY, NEW JERSEY.

PUNCHING-MACHINE.

SPECIFICATION forming part of Letters Patent No. 257,240, dated May 2, 1882.

Application filed September 30, 1881. (No model.)

To all whom it may concern:

Be it known that I, JOHN M. RILEY, a citizen of the United States, residing at Kearney, in the county of Hudson and State of New Jersey, have invented certain new and useful Improvements in Punching-Machines; and I do hereby declare the following to be a full, clear, and exact description of the invention, reference being had to the accompanying drawings, which form part of this specification, and in which—

Figure 1 is a perspective view of my improved punching-machine, and Fig. 2 is a sectional view of the same.

15 My invention relates to punching-machines of that class in which two or more punches are used to effect the simultaneous punching of any desired object at two or more points and from different sides or directions.

20 The object of my invention is to provide means whereby an object may be punched out at two or more places by the same number of punches working simultaneously toward a common center.

25 It has also for its object the provision of means whereby the several punch-slides used may be connected to a single treadle-rod or other suitable actuating device.

Referring to the accompanying drawings, 30 which illustrate my invention, A represents a work bench or table, on which is supported the punching-machine B by legs a a. A die, C, of form adapted to the particular class of work which is to be operated upon, is secured 35 to the base B of the machine, at or near its center, by screws c c.

D D' D D' are guide-plates secured to the base on opposite sides of the die C, forming dovetailed ways for the punch-slides E E'. These 40 slides are provided with the removable punches e e', which register with holes d d' in the sides of the die C. The slides E E' extend beyond the ends of the base B, and have downwardly-projecting shoulders F F', in which set-screws 45 f f' work, the object of said set-screws being to limit the inward movement of slides E E'.

Depending from the slides E E', and projecting through an opening, b b', in the base B, are two flat blocks, G G'. These blocks are 50 set in slots g g' in the slides E E', and are held in place by fastening-plates h h', secured to said blocks by screws i i.

Attached to the base B, on the under side thereof and below the slides E E', are hangers H H'. Between said hangers, and attached thereto by pivots k k', are two levers, L L'. These levers have upwardly-projecting arms l l', which are provided with round heads m m', fitting in sockets n n' in the blocks G G' and forming a socket-joint therein. 55

M M' are adjustable weights on the outer ends of the levers L L'. These weights are intended to counterbalance the levers L L' and assist in withdrawing the punches e e' from the die. The levers L L' lap over at their inner 60 ends, and are attached to the head O of the treadle-rod P by straps o o'.

The operation of my invention is as follows: The work which is to be punched having been placed in position on the base B, the treadle-rod P is depressed and the inner ends of the levers L L' brought down toward the table A. The arms l l' move the blocks G G' toward the die, thus causing the punches e e' to effect their intended purpose simultaneously. After the 70 punching has been completed the rod P is released and the levers L L' return to their normal position.

It will be observed that the punches move forward toward the die on the same line, and 80 that the holes are punched at points which are exactly opposite one another. This is of great importance in certain classes of work—as, for instance, in punching the rivet-holes in satchel and pocket-book frames or clasps, for hollow 85 keys of accordions, &c.

When it is desired to change the character of the work—as, for instance, from pocket-book to satchel frames—the die and punches are removed and replaced by others of a suitable 90 character. The punch-slides are then adjusted on the blocks, so as to give a suitable range of motion to the punches, and the set-screws fixed to limit the inward movement of the slides and their contained punches. 95

I have described and shown a punch adapted to punch two holes in opposite sides of a piece of work; but I do not limit myself to this construction, as the punch-slides and their actuating devices may be increased in number 100 without departing from the spirit of my invention.

Having described my invention, I claim—
1. In a punching-machine, the combination

of the punch-slides E E', having the slots $g g'$, with the adjustable blocks G G' and levers L L', all constructed and arranged substantially as described.

5 2. In a punching-machine, the combination of the actuating-levers L' L and blocks G G', secured to the slides E E' and adjustable therein, with the removable die C, substantially as shown and described.

10 3. In a punching-machine, the slides E E', having the shoulders F F' and set-screws f f', in combination with the adjustable blocks G G' and levers L L', constructed and arranged substantially as and for the purpose described.

15 4. In a punching-machine having separately-adjustable punch-slides, and actuating-levers for causing the punch-slides to simultaneously operate upon opposite sides of a die, the com-

bination, with such punch-slides and actuating-levers, of separately-adjustable counterbalance-weights, substantially as and for the purpose described.

5. In a punching-machine, the combination of the slides E E' and blocks G G', adjustable in said slides, with the levers L L', having arms l l', weights M M', and straps o o' to attach the said levers to the treadle-rod O, the said parts being constructed and arranged substantially as and for the purpose described.

In testimony that I claim the foregoing I have hereunto set my hand this 6th day of August, 1881.

JOHN M. RILEY.
